BATHTUB

Ethel N. Bassett, Lincoln, Nebr.

Application May 26, 1936, Serial No. 81,828

5 Claims. (Cl. 4—173)

My invention relates to bath tubs, its primary object being the provision of a bath tub which is especially adapted to be occupied in a comfortably reclining position.

5 Another of the objects is the provision of a bath tub having a basin for use as a foot bath and accompanied by a seat which may be occupied while taking a foot bath.

Another object of the invention is the provision of a back rest for supporting the user at 10 a comfortable inclination together with a basin for receiving the feet, a wall of the basin being inclined for comfortably resting the feet while the user is lying in the bath tub.

15 Another very important object of the invention is the provision of a back rest, seat, foot basin and foot rest with means for draining the seat into the basin and means for discharging the contents of the bath tub into the house drain, 20 the parts being so arranged that they may be kept in clean and sanitary condition with the minimum of effort.

Having in view these objects and others which will be pointed out in the following description, 25 I will now refer to the drawing, in which

Figure 1 is a plan view of my bath tub.

Figure 2 is a view in longitudinal section on the line 2—2 of Figure 1.

Figure 3 is a view in transverse section on the 30 line 3—3 of Figures 1 and 2.

In external appearance and in general dimensions, my bath tub resembles the standardized bath tub at present extensively in use. It differs from the prior bath tubs mainly in the shape 35 and function of the bottom or floor of the bath tub.

As shown in my drawing, the floor is elevated 40 at the head of the bath tub so that the end of the floor is but very slightly below the upper rim of the bath tub at the head. This portion 45 of the floor has a gentle slope downwardly and toward the rear or foot wall and it merges into the substantially horizontal seat portion 11 which has a very slight inclination upwardly and toward the rear end of the bath tub. The seat portion merges into a rearwardly and downwardly inclined wall portion 12 which in turn merges into the substantially horizontal foot portion 13. At the end of this portion 13 is a foot rest portion 14 which is upwardly and rearwardly inclined and which in turn merges into the rear or foot wall 15 of the bath tub.

The installation of my bath tub is similar to prior installations in having an inlet valve 16 and a drain 17, the latter being usually provided

with the common bath tub plug. In most other respects the bath tub and its installation are similar to the prior bath tubs.

The parts 10, 12 and 14 all drain readily toward the portion 13 but the portion 11 has a very slight inclination upwardly and toward the rear which prevents its complete drainage of the seat. For draining this portion 11 I provide a groove 18 which, as shown in Figure 2, has a distinct drainage toward the portion 14. 10

The bath tub is designed for use in reclining as well as in sitting and standing. If the bath is to be taken standing up, the user simply stands on the portion 13 of the floor and he may then use a sponge or a shower which may be installed 15 above the bath tub. If he wishes to take a foot bath alone, he fills the bottom portion 13. If he wishes to assume a restful position and to recline partially submerged in the bath tub for any length of time he assumes the posture indicated in Figure 2 with his shoulders resting on the portion 10 and with his buttocks resting on the portions 10 and 11 at the curved portion between the portions 10 and 11. The feet may rest either on the floor portion 13 or on the foot 25 rest 14 depending on the height of the user. The head may rest directly on the portion 10 but if desired a pillow 19 of sponge rubber or similar material may be employed.

From the above description and the illustrations in the drawing, it will be seen that the bath tube may be employed for all of the uses possible with the common bath tub and that it has a number of important uses in addition. If used as a foot bath, the lower basin is filled with 35 water and the user may rest his feet in the water while he is either sitting on the seat 11 or reclining on the back rest 10 and the seat 11. A shower or sponge bath may be taken by standing on the foot support 13. Primarily, however, 40 the bath tube enables the user to occupy a position of perfect repose as shown in Figure 2 and to take a bath over an extended period of time without any discomfort whatever. This may be done to obtain the advantages of the refreshment accompanying such a bath. The bather may read a book while he is in the bath or he may even take a nap in this position. The use of the bath tub in hydrotherapy, both in 45 the home and in the hospital will also be obvious.

While utility and comfort are of primary importance in the design of my bath tub, cleanliness was also considered. The back rest 10 50 drains readily onto and over the seat 11 and into

the foot basin. This foot basin is provided with the usual drain so that the bath tub may easily be kept clean with a minimum of brushing. The seat being slightly inclined would be apt to hold 5 a small amount of water but the special provision of the trough 18 causes the water from the seat to drain through that trough and into the basin.

Because of the shallow depth of the major portion of my bath tub most of the floor space can be reached and cleaned with the minimum of stooping. My bath tub provides new reclining comfort and relaxation and it is equally suitable for child or adult. A new sitting comfort is also 10 provided by lowering the feet below the sitting level. In this new sitting position the bather has the maximum comfort, free from pressure upon the abdominal muscles and from all tension on the muscles in the back of the legs. These discomforts can not be avoided when sitting in a flat bottomed bath tub where the legs have to be 15 extended at right angles to the body. The foot rest coincides with the angle which the feet naturally assume. The foot basin is of a depth which 20 accommodates both children and adults.

An important advantage of my invention is the greatly reduced water consumption due to the fact that there is no unused space behind the bather to be filled. The water being concentrated 25 around the bather, the amount of water used is thus proportional to the size of the user. There is also a great water saving in the foot bath since only the foot basin need be filled, not the entire tub floor covered as is necessary in other tubs. 30 The smaller water consumption provides another convenience especially in homes where there is only one tub in that the tub empties more quickly, thus enabling the whole family to bathe in less time. The elevated seat is a feature which 35 provides an ideal arrangement for bathing little tots as it places them within convenient reach that the mother or nurse can give the bath with the greatest of ease and dispatch. My tub may also be used as a steam bath for reducing, it being 40 necessary only to place a stool or some suitable device in the foot basin for elevating the feet above the water and to cover the tub with a sheet.

Having thus described my invention in such full, clear, and exact terms that its construction 45 and operation will be readily understood by others skilled in the art to which it pertains, what I claim as new and desire to secure by Letters Patent of the United States is:

1. A bath tub having a floor including a head 50 and back support inclined downwardly and away from the head wall of the bath tub, a seat slightly inclined upwardly and toward the foot wall of the bath tub, a substantially horizontal foot support positioned below the level of said seat, a wall 55 between said seat and said foot support, said wall being abruptly inclined downwardly and toward

the foot wall of said bath tub, a drain in said foot support, and a foot rest inclined upwardly and away from said foot support, said foot rest merging into the foot wall of said bath tub.

2. A bath tub having a head wall and a foot wall and side walls and a floor, said floor including a combined head and back support gently inclined downwardly and away from said head wall, a seat slightly inclined upwardly and toward said foot wall, a substantially horizontal foot support positioned below the level of said seat and away therefrom in the direction toward said foot wall, and a downwardly projecting wall between said seat and said foot support, the arrangement providing a depressed basin between said downwardly projecting wall and of said foot wall and portions of said side walls, and a drain in said foot support. 5 10 15

3. A bath tub having side walls and having head and foot walls at its respective ends, and a floor between the side and end walls of said bath tub, said floor including a back support inclined downwardly from the upper portion of the head wall of the bath tub to a position substantially midway between the head and the foot 20 walls of the bath tub, a seat continuous with said back support and inclined upwardly and away therefrom, a downwardly projecting wall continuous with said seat, a substantially horizontal foot support projecting from the forward edge 25 of said downwardly projecting wall, a foot rest inclined upwardly and toward the foot wall of said bath tub, said foot rest being continuous with said foot wall and with said foot support, said downwardly projecting wall and said foot rest 30 and said foot support with portions of said side walls enclosing a depressed basin, a drain in said basin, and a depressed groove in said seat for draining the water from said seat into said basin. 35

4. In a bath tub, a foot basin, a substantially horizontal seat projecting outwardly and away from the upper edge of said foot basin, and an inclined back and head rest projecting from said seat, said foot basin, seat, and back and head rest being of integral construction, and the overall length of said foot basin and said seat being substantially equal to the length of said back and head rest whereby the bather may comfortably occupy said seat in either upright or reclining position. 40 45 50

5. A bath tub having a floor, including a head and back support inclined downwardly and away from the head wall of the bath tub, a foot wall, a substantially horizontal elevated seat complementary to said inclined support, a substantially horizontal foot support positioned below the level of said seat, a substantially vertical wall between said seat and said foot support, and a drain in said foot support. 55
